UNITED STATES PATENT OFFICE

JOSEPH ZUBATY, OF FLINT, MICHIGAN

FUEL PUMP

Application filed March 9, 1928. Serial No. 260,419.

This invention is concerned with the fuel supply for an internal combustion engine and particularly for an engine employing a supercharger and one wherein the fuel is supplied to the carburetor by an engine operated fuel pump.

An object of the invention is to provide an improved fuel pump for use with an internal combustion engine having associated therewith a supercharger placed before the carburetor and compressing air only. More specifically, the invention provides a pump having a discharge stroke the efficiency of which is made variable and which efficiency is automatically changed to supply fuel to the carburetor at a pressure dependent upon the air pressure delivered to the carburetor by the supercharger. Other objects and advantages will be understood from the following description and from an examination of the accompanying drawing.

In the drawing:

Figure 1 is a side elevation of an internal combustion engine, such as is used on motor vehicles, the engine having my improvements associated therewith.

Figure 2 is a vertical section through parts of the fuel supply system.

Figure 3 is a horizontal section on line 3—3 of Figure 2.

Referring by reference characters to the drawing, numeral 5 is used to designate an internal combustion engine. The invention is concerned only with the fuel system for the engine and other parts will not be included in this description. Numeral 7 is used to designate an intake manifold and 9 a header therefor connected to a carburetor 11 by fastening means 13.

An air cleaner 15 of any preferred kind may be used. If such an air cleaner is used, it will be connected to a supercharger 17 for delivering air to the carburetor. The structure of this supercharger need not be described as the details of the supercharger are

no part of this invention. The supercharger draws air through the cleaner 15, if such cleaner is used, and delivers the air at super-atmospheric pressure to the air inlet tube 23 of the carburetor 11, the air under high pressure passing through the header 9, manifold 7 and into the engine cylinders.

In such a system, the pressure in the venturi of the carburetor may become sufficiently high to oppose the flow of fuel from the float chamber. This difficulty is remedied by sealing the float chamber 21 and connecting the sealed float chamber with the air tube 23 of the carburetor by a suitable conduit 19 as shown in Figure 1. This provision assures an ample fuel flow even when the pressure in tube 23 is above atmospheric.

Numeral 25 represents a fuel pump having a diaphragm 27 confined between body 29 and its cover 31. The cover 31 is preferably extended beyond the pump body and to the extension may be secured a filter cup 33. A bail 35 is attached to the cover extension and surrounds the cup 33. A screw eye 37 has its eye portion encircling the bail beneath the cup 33 and an adjusting nut 39 may be threaded up on the threaded part of the screw eye to hold firmly against the bottom of the cup a support 41. This is described as a convenient and preferred form of cup support but these details do not form a part of this invention.

The cover 31 has an inlet 43 communicating with the fuel reservoir. When the subject matter of this invention is used in connection with motor vehicles, the fuel reservoir will obviously be the tank usually carried in a low position at the rear of the vehicle. From the inlet 43 and angular passage 45 conducts the fuel to an opening or openings 47 communicating with the interior of the fuel cup and beneath suitable filtering means 49. Filtered by said filtering means, the fuel may pass an inlet valve designated by numeral 51 and preferably located in the cover mem-

ber. From valve 51 the fuel passes through passage 53 to the variable volume pump chamber of the pump 25. This chamber is constituted by the flexible diaphragm 27 and the cover 31. An outlet valve 55 of any preferred form is also located preferably in the cover member 31 and controls a discharge from the pump chamber to the pipe 57 leading to the float chamber of the carburetor.

5 The diaphragm 27 is reinforced by discs 59 and connected by a rod 61 with a collapsible link member 63 to be connected to suitable operating means. This operating means may be of some other type but is preferably in 10 the form of a lever pivoted to the pump body, one end of the lever engaging the lower end of the collapsible link and the other end of the link actuated by the cam of the camshaft. This construction is not illustrated as it is 15 well-known and constitutes no part of this invention. By this arrangement, the operating means may, through the instrumentality of the collapsible link, pull down upon the diaphragm to make a suction stroke. The 20 discharge stroke is preferably made by a coil spring 65 engaging the lower disc 59 and also an abutment in the pump body. In the usual use of such a pump where no supercharger is employed, the lower abutment for spring 25 30 is fixed. In the present form, however, an automatically variable lower abutment is made use of as described below. In use, the collapsible link pulls down upon the diaphragm only after being straightened out 35 to a predetermined extent. Should the pressure in the pump chamber be high, spring 65 may be under compression and the diaphragm be depressed sufficiently to at times prevent any suction stroke. By this means, the diaphragm 40 is not unnecessarily flexed, being flexed only when needed to discharge fuel and to draw in fuel to replace that used by the carburetor.

Under the circumstances described above, 45 where a supercharger is used and the float chamber is sealed and under super-atmospheric pressure, the discharge operating spring 65 of pump 25 may not be sufficiently effective to overcome the pressure in the float 50 chamber which the pump supplies. This invention has been made to correct this difficulty by giving to spring 65 added efficiency in proportion to the added burden to which it may be subjected. To this end instead of 55 providing a fixed abutment beneath spring 65, there is a variable abutment. A lower disc 67 has an upper cam surface engaging a similar cam surface on the lower face of an upper cam disc 69. The spring rests on 60 the upper disc 69. Means are provided to rotate disc 69 on disc 67 to thereby raise the lower spring abutment and add to its effective pressure in producing the discharge stroke of the pump. To accomplish this purpose 65 the upper disc 65 is provided with a radial

arm 71 extending through the wall of the pump body, as shown in Figure 3, where it is connected to a link 73. Located preferably in a position near the pump is a chambered member 75 having a cover 77. Clamped 70 between the body 75 and the cover 77 is a flexible diaphragm 81. A plunger 83 is secured to the center of the diaphragm by washer 85 and a nut 87. This plunger 83 passes through an opening in the body portion 75 and is connected to one end of link 73. The cover 77 is provided with an opening 91 to which is secured the end of a conduit 93, which also communicates with the air tube 23 of the carburetor. By this means, the air pressure in the air tube 23 is communicated to the chamber defined by cover 77 and diaphragm 81. One or more breather openings 95 are provided in the chamber 75 to keep the air therein at atmospheric pressure and make possible a flexing of the diaphragm 81 with changing pressures in the air tube of the carburetor. A spring 97 is placed on the atmospheric side of diaphragm 81 to return the diaphragm 90 to its former position after being moved inwardly by air pressure. It will be understood that such inward movement reciprocates plunger 83 and link 73 and rocks disc 69 upon disc 67 whereupon the cam surfaces cause the rising of the lower abutment of spring 65. As a result spring 65 is rendered 95 more effective in overcoming the fluid pressure in the pump chamber and thereby more effective in discharging fuel from the pump to the sealed float chamber of the carburetor. It will be understood that simultaneously with increased pressure in the float chamber due to pipe 19 the pressure on diaphragm 81 is increased and spring 65 is given additional 100 efficiency to deliver fuel to the carburetor.

While but one mechanical connection between the lower spring abutment and the control chamber 75 is herein described, it will be of course understood that other connections to accomplish the same result may be resorted to. A double arm lever, for example, might be pivoted to the pump chamber having one arm actuated by the connected link 73 and the other operable to raise the movable abutment for spring 65. Numerous other expedients will be obvious.

By the arrangement described, there is provided a fuel pump operable by resilient means on its discharge stroke and which resilient means is rendered automatically variably effective in proportion to the variable need for a discharge stroke dependent upon the pressure in a sealed float chamber. The result is accomplished by means both simple and inexpensive.

I claim:

1. In a fuel supply system for internal combustion engines, a carburetor having a sealed float chamber and an air inlet, a supercharger delivering air under pressure to

said air inlet, a conduit from said air inlet to said float chamber, a pump having a yielding member to effect a discharge stroke, a movable abutment therefor, a variable volume chamber, a conduit therefrom to said air inlet, a plunger reciprocable by air pressure in said chamber, said plunger operably connected to said variable abutment whereby the potential energy of the yielding member

10 is modified by movements of the plunger.

2. The invention defined by claim 1, said movable abutment comprising a movable cam member, a fixed cam member in engagement therewith, the first-named cam member

15 serving as an abutment for the yielding member.

3. The invention defined by claim 1, said movable abutment comprising a rotatable disc having a cam face, a fixed disc having a 20 co-operating cam face, said first-named disc serving as an abutment for said yielding member and provided with an arm, said plunger connected to said arm.

4. In a fuel supply system for internal 25 combustion engines, a carburetor having a sealed float chamber and an air inlet, a supercharger delivering air under pressure to said air inlet, a conduit from said air inlet to said float chamber, a variable stroke pump delivering fuel to said float chamber, said pump comprising a collapsible linkage to effect the suction stroke and a spring to effect the discharge stroke whereby the length of the stroke is dependent on the pressure in the 35 float chamber, a movable abutment for said spring to vary the pressure exerted thereby during the discharge stroke, and means to automatically control the position of said abutment by the air pressure in the carburetor air inlet.

5. In a fuel supply system for internal combustion engines, a carburetor having a sealed float chamber and an air inlet, a supercharger delivering air under pressure to said 45 air inlet, a conduit from said air inlet to said float chamber, a variable stroke pump delivering fuel to said float chamber, said pump comprising lost motion means to effect the suction stroke and yielding means to effect the discharge stroke whereby the length of the stroke is dependent on the pressure in the float chamber, a movable abutment for said yielding means to vary the pressure exerted thereby during the discharge stroke, 55 and means to automatically control the position of said abutment by the air pressure in the carburetor air inlet.

6. In a fuel supply system for internal combustion engines, a carburetor having a 60 sealed float chamber and an air inlet, means to supply air under pressure to said air inlet, a conduit from said inlet to said float chamber, a fuel pump, a conduit from said pump to said float chamber, said pump having 65 yielding means as the sole agency to effect a

discharge stroke, means operable by the pressure of the air in the air tube of the carburetor to vary the potential energy of said yielding means, said pump discharge means comprising a spring having a movable abutment, and said pressure operated means for varying the spring pressure comprising a closed chamber, a conduit from said inlet tube to said closed chamber, a plunger movable by the air pressure in said chamber, said plunger operably connected to said movable abutment.

In testimony whereof I affix my signature.
JOSEPH ZUBATY.
